[57] CLAIM

The ornamental design for the control panel for electronic copying machine, as shown and described.

DESCRIPTION

FIG. 1 is a top, front and left side perspective view of a control panel for an electronic copying machine showing our new design;

FIG. 2 is a front elevation view thereof;

FIG. 3 is a top elevation view thereof;

FIG. 4 is a rear elevation view thereof;

FIG. 5 is a bottom elevation view thereof;

FIG. 6 is a left side elevation view thereof;

FIG. 7 is a right side elevation view thereof; and,
FIG. 8 is a top, front and left side perspective view thereof,
the broken line showing of an electronic copying machine is
for illustrative purposes only and forms no part of the
claimed design.
